UNITED STATES PATENT OFFICE.

WILLIAM M. HUTCHISON, OF SOMERVILLE, NEW JERSEY, ASSIGNOR TO UNION TANK LINE COMPANY, OF NEW YORK, N. Y., A CORPORATION OF NEW JERSEY.

TANK.

1,329,603.

Specification of Letters Patent.

Patented Feb. 3, 1920.

Application filed January 25, 1916. Serial No. 74,085.

To all whom it may concern:

Be it known that I, WILLIAM M. HUTCHISON, a citizen of the United States, residing at Somerville, in the county of Somerset and 5 State of New Jersey, have invented certain new and useful Improvements in Tanks, of which the following is a specification.

My invention relates to new and useful improvements in tanks and especially trans- 10 porting tanks of that character or type mounted upon trucks for transportation along a railway, and more particularly contemplates an improved tank for the transportation of fluid substances which congeal 15 or solidify, such, for instance, as asphalt, pitch and oleaginous substances which, upon cooling, harden to such an extent as to be no longer fluid or which flow only with great difficulty, and for this reason consume an 20 objectionably long period of time in being flowed from the tank when it is desired to withdraw the substance therefrom.

The primary object of my invention is to provide an improved tank which will have 25 an efficient heating means for heating the congealed or solidified contents to reduce the same to such fluid state as will permit it to flow rapidly and freely from the tank.

A further object of the invention is to pro- 30 vide a heating system, the parts of which may be readily and conveniently accessible for repair and replacement.

A further object is to provide a heating means which will efficiently reduce the 35 solidified contents of the tank about the outlet opening or in the spout leading from the same, should a spout be employed and to prevent such coagulation or solidification during the emptying of the tank as would 40 restrict the outlet opening.

A further object is to provide an im- 45 proved heating system in the tank which will evenly and quickly distribute its heat throughout the contained mass resulting in a rapid and even melting of the said mass to a fluid condition.

Another object is to provide means for efficiently and rapidly heating contents surrounding the valve and valve-seat of the

tank outlet, and the means for operating the 50 valve, so that the valve may be easily operated.

The invention consists in the means to be more fully described hereinafter and the novelty of which will be particularly pointed out and distinctly claimed.

I have fully and clearly illustrated my invention in the accompanying drawings to be taken as a part of this specification and wherein:

Fig. 1 is a horizontal longitudinal section through a tank equipped with my invention.

Fig. 2 is an enlarged vertical central section through the central portion of the tank 65 longitudinally thereof, shown in Fig. 1.

Fig. 3 is an end view of the tank body with one of the heads thereof removed to show the internal arrangement of some of the heating elements at the end of the tank, 70 some of the parts being omitted for the sake of clearness.

Fig. 4 is a section on the line 4—4 of Fig. 2.

Fig. 5 is a detail top plan view of an outlet spout.

Fig. 6 is a detail sectional view of a means for attaching one of the heating elements to the wall of the tank body.

Referring to the drawings by characters of reference, 1 designates a shell or body of a tank of one type to which my invention is applicable, said body being built up of sheet metal plate or plates in a well-known manner, and being cylindrical in form and adapted to be supported upon wheeled trucks (not shown) to constitute a tank car, the ends of said shell being closed by crown heads of sheet metal 2, 2. The tank body may be provided at a point intermediate its ends and on its upper side with a vertically-extending dome 3 of well-known construction. I desire it understood that I do not limit myself to the particular type or construction of the tank body proper, as my invention is applicable to different types and 90 constructions of tank bodies.

The tank body is adapted to receive and transport liquids, and, in the present in-

stance, substances which, for one reason or another, such as cooling, are liable to congeal or harden so as to be non-fluent, or to flow with difficulty when it is desired to 5 empty the tank. At a point intermediate its ends the tank body is provided with an outlet opening 4 which opens into an unloading nozzle 5 secured at one end to the shell of the tank in any suitable manner and having 10 at its free end a threaded portion 6 for connection to a hose to lead the tank contents to any desired point. This unloading nozzle 5 is provided at a point adjacent the opening 4 with a valve-seat 7 with which 15 cooperates a vertically reciprocating valve 8 adapted to be operated by a valve stem or rod 9 extending into the dome 3 for access by an operator. The valve is guided in its vertical movements to and from its seat by 20 a guide-rod 10 sliding through an opening 11 in a web 12 extending transversely of the unloading nozzle. The spout is provided at a point adjacent the valve-seat, and for some distance below the same, with an annular chamber 13 adapted to receive a heating medium such, for instance, as steam, hot oil, hot air, etc., whereby the valve-seat and the wall of the unloading nozzle are heated thereby heating the substance in the tank 25 so that the valve will not become set to the seat by the congealed mass or by freezing, and a clear passage will be maintained through the unloading nozzle. For cheapness in manufacture and efficiency in results, 30 I prefer to make the said spout, the valve-seat, the heating chamber and the guide-web in an integral casting, but it will be understood that this construction may be modified without departing from my invention. 35 Arranged within the tank body is a heating means adapted to evenly and rapidly heat the material in the tank body to provide for the flow of the same from the tank, which means I will now describe. 14 designates a header or distributing chamber 40 preferably in the form of a horizontal tubular casting arranged transversely of the tank at a point substantially midway the ends of the latter, and at a point substantially at the horizontal center of the tank, as clearly indicated in Figs. 2 and 4. This header is provided at each of its opposite ends with oppositely-directed outlet necks or couplings shown respectively at 15, 16, 45 and 17, 18. Connected to the coupling 16 is one end 19 of a heating conduit 20, the latter being extended longitudinally of the tank to a point adjacent one end thereof, and then directed across the head, as at 21, 50 to form a loop, as clearly shown in Figs. 1 and 3, at a point approximating a horizontal plane extending through the longitudinal axis of the tank, the return bend of the loop being carried back to the side 55 of the tank, as shown, and extended to a point adjacent the header, from which point said pipe 20 is carried back and forth in loops 22. These loops are arranged to conform to the contour of the interior of the tank and closely approaching the inner 60 surface of the tank wall, but are spaced therefrom, as shown in Figs. 3 and 4, so as to permit the fluid to flow readily between said loops and the tank wall and also to permit of the expansion and contraction of the pipes. The loops are supported at 65 points adjacent the center of the tank and the end of the latter by transverse supporting bars 23, 24, preferably curved to conform to the contour of the tank and be 70 parallel thereto, and having their ends riveted to the side walls of the tank, as shown at 25. The loops are supported on the under side of said bar by hook clamps or U bolts 26 engaging the loops and secured to a flange 27 of said bars by means of nuts 28 threaded on the shanks on said bolts. It will be understood that any other means of fastening which will permit of 75 expansion and contraction of the pipes may 80 be employed. The transverse loop 21 is secured in position against the head of the tank by a bracket 29 riveted to said head, said loop being connected to the bracket by means of a U-bolt 30. The last return 31 of the conduit 20 is carried to a point adjacent the outlet opening 4, heretofore described, and is deflected around the same, as at 32, and is connected at its outlet end to an outlet header which will now be described. This outlet header consists of a 85 central chamber or conduit 33 located adjacent the lowermost portion of the tank and extending transversely of the latter and provided at its opposite ends with pairs of 90 coupling necks shown respectively at 34, 35, and 36, 37, the deflected outlet end 32 of the pipe 20 being connected to the neck 35, as clearly shown in Fig. 1 of the drawings. The chamber 33 is provided with a 95 depending neck 38 having a passage communicating with the interior of said chamber and opening through the wall of the tank into a pipe 39 which is connected to the chamber 13, heretofore described, said 100 neck being preferably flanged and secured to the wall of the tank by any suitable means. 105 Connected to the coupling 18 on the header 14 is one end of a back-and-forth pipe coil 110 40 which is arranged similar to the pipe 20, heretofore described, having an end loop 41 similar to the loop 21, heretofore described, the outlet end of said coil 40 being connected to the neck 37 of the outlet 115 header 33. 120 Connected to the neck 15 on the header 14 is one end of a back-and-forth pipe coil

arrangement 42 located in a manner similar to the coils 20 and 40, heretofore described, but extending in the opposite direction thereto from the header 14, having an end 5 loop 43 extending across the end of the tank head 2 at the opposite end of the tank from the loops 21 and 41. The return end of the pipe 42 is connected to the neck 34 of the outlet chamber 33, as shown at 44. To the 10 coupling neck 17 of the header 14 is connected the inlet end of another back-and-forth arrangement of pipe 45 having a loop 46 at the end of the tank extending 15 toward said loop 43, the outlet end of the pipe 45 being connected to the coupling neck 36 of the outlet chamber, as at 47. One or more of the return loops of the pipe 45 adjacent the bottom of the tank and the header 33, may be shortened, as at 20 48, to provide a space for the accommodation of the said outlet chamber.

Steam or other fluid heating medium is supplied to the inlet header 14 by means of a supply pipe 49 coupled to said header, as at 25 50, and having its opposite end projecting through the side wall of the dome 3, or through the tank wall at some other point, and suitably secured to said wall by means of clamping nuts 51, the outer end of the 30 said supply pipe being threaded, as at 52, to receive a closure cap 53. The inlet end of this pipe is adapted to be connected to a steam line whereby steam is fed to the header 14 preferably at the center thereof 35 and is distributed therefrom through the couplings 15, 16, 17 and 18 to the independent sets of heating units 20, 40, 42 and 45. The steam line may enter the header at any point intermediate to the center and ends of 40 the header. The arrangement of independent heating units is important because the heating medium, such as steam, will pass simultaneously through all of said units and be distributed through the heating system 45 more rapidly than were the whole system of pipes in a continuous circulatory arrangement. Another advantage is that one of the units may be removed or repaired without disturbing or disconnecting the others. The 50 pipe systems 42 and 45 are supported by supporting bars 23', 24', similar to the bars 23 and 24, heretofore described, and the loops 43 and 46 are supported in the same manner as the loops 21 and 41, and it is, 55 therefore, believed that further description of this supporting means is unnecessary.

The steam fed to the header 14 passes to the several heating units and is exhausted therefrom into the exhaust or outlet chamber 60 33, from which it passes into the pipe 39 and through the chamber 13, heretofore described, in the unloading nozzle, whence it is exhausted by an exhaust pipe 54. It will thus be seen that the base portion of the sub-

stance within the tank will be heated and 65 melted, and that the unloading nozzle will be heated so as to melt out any substance adjacent to the valve and valve rod which may serve to lock the valve to the valve seat and also provide a free passage through the 70 unloading nozzle.

It is important, as far as the element of time-saving is concerned, that the material adjacent the valve be melted quickly to provide a free passage to the unloading nozzle, 75 so that the fluid resulting from the melting of the substance in the tank may find a ready outlet. In order to accomplish this result, I preferably provide a heating means whereby the substance being transported adjacent 80 the valve and the outlet will be heated by the steam or other heating medium while the latter is at its highest temperature so that, in effect, a passageway is provided promptly 85 for access of the melted substance to the outlet. This means may take a number of forms, but I prefer to provide a helical pipe coil 55 wound vertically around the valve-stem 9 and spaced therefrom, said coil being of such length as may be necessary to melt 90 enough of the substance about the valve-stem and valve to open up the passageway to the valve and the outlet. In order that the pipe coil may receive the heating medium at its highest temperature, the upper 95 end of said coil preferably is connected directly to the header 14, as at 56, directly beneath the coupling 50 so that the coil 55 is in effect in direct communication with the inlet pipe 49. The outlet of the coil 55 may 100 take place at any point, but I prefer to couple it, as at 57, to the outlet chamber 33 so that the highly heated steam will also enter the outlet chamber and will maintain 105 the spout connected thereto at a higher temperature than if only the exhaust steam from the main heating coils were admitted to said chamber 13.

It is believed that the operation of the tank embodying my invention will be clearly 110 understood from the above description taken in connection with the drawings, but I will briefly state the operation as follows, it being assumed that the tank contains a fluid substance which has congealed or solidified to such an extent as to reduce its ability to flow rapidly from the outlet of the tank: The operator removes the cap 53 from the steam supply pipe 49 and connects to said pipe a steam conduit leading to any suitable 115 source, and the steam is then permitted to flow through the supply pipe into the header 14, whence, at its high temperature, it flows directly into the coil 55 surrounding the valve-stem 9, thus melting the substance 120 surrounding the valve-stem so as to permit the easy operation of the latter. From the coil 55 the steam passes into the outlet header 125

or chamber 33, whence it passes through the pipe 39 to the chamber 13 so that the spout and the portion thereof around the valve and valve-seat is heated to melt any of the substance which would obstruct the flow through the unloading nozzle or tend to set the valve to the seat. Some of the steam which has entered the header 14 passes through the coupling necks at the ends thereof into the heating pipes 20, 40, 42 and 45, so that the sides and bottom portion of the substance contained in the tank is heated to the point where it will flow readily from the tank body. By spacing the heating units from the wall of the tank, it will be apparent that they do not obstruct the flow of the melted substance, as would be the case were they located against, or too close to, the wall of the tank.

20. What I claim and desire to secure by Letters Patent of the United States is:—

1. In a tank, inlet and outlet headers in the tank, a heating conduit having its inlet end connected to the inlet header, and its 25 exhaust end connected to the outlet header, the said conduit extending longitudinally of the tank to a point adjacent to one end thereof and then being directed across the end of the tank in the form of a loop closely approaching the inner surface of the tank wall.

2. In a tank, an inlet header extending within and transversely of the tank, the said inlet header having oppositely-disposed 35 branches at its ends, an outlet header having oppositely-disposed branches, pipe coils having their inlet ends connected to the branches of the inlet header and their exhaust ends connected to the branches of the 40 outlet header, the said coils extending longitudinally of the tank and being formed at each end of the tank with transverse oppositely-extending loops.

3. In a tank having a discharge opening, 45 a valve controlling said opening, a valve rod for operating the valve, inlet and outlet headers in the tank, heating conduits having their respective ends connected to said headers, and a heating pipe connected with the 50 inlet header and extending adjacent and longitudinally of the valve rod.

4. A tank having a discharge opening, an unloading nozzle leading from said opening and containing a heating chamber exterior 55 of the tank, an inlet header and an outlet header in the tank, a heating conduit connecting said headers and extending longitudinally of the tank and adjacent the wall thereof, a heating coil surrounding the 60 discharge opening within the tank and connected to said headers, and an exhaust connection between the outlet header and said chamber.

5. In a tank, an inlet header in the tank

provided with a discharge opening and extending transversely thereof, an outlet header in the tank, a back-and-forth heating conduit connected at one end to the inlet header and at the other end to the outlet header, and a pipe coil surrounding said 70 discharge opening and connected at its ends to said headers.

6. In a tank, an inlet header in the tank and extending transversely thereof adjacent the horizontal diameter of the tank, an outlet header arranged adjacent the inlet header and beneath the same, and independent sets of heating conduits extending in opposite directions from said headers and having their inlet ends connected to the inlet header and their outlet ends connected to the outlet header. .

7. In a tank, an inlet header in the tank and extending transversely thereof and having oppositely-disposed discharges at its 35 ends, an outlet header having oppositely-disposed inlets at its ends, and independent sets of heating pipes extending in opposite directions from said headers and having their inlet ends connected respectively to the discharges of the inlet header and their outlet ends connected to the inlets of the outlet header.

8. In a tank, an inlet header in the tank and extending transversely thereof and having oppositely-disposed discharges at its ends, an outlet header having oppositely-disposed inlets at its ends, and independent sets of heating pipes having their inlet ends connected respectively to the discharges of 100 the inlet header and their outlet ends to the inlets of the outlet header, said outlet header being supported below the inlet header by the lower portion of the wall of the tank and having an exhaust therethrough. 105

9. In a tank car, a tank having a discharge outlet through its lower wall, a valve for controlling said outlet, a valve-rod connected to said valve and extending through the space within the tank, and a heating 110 member surrounding said valve-rod.

10. In a tank car, a tank having a discharge opening through its lower wall, a valve for controlling said outlet, a valve-rod connected to said valve and extending 115 through the space within the tank, and a heating member surrounding said valve-rod, said heating member consisting of a pipe coil arranged with its longitudinal axes substantially coincident with the longitudinal 120 axis of the valve-rod.

11. In a tank car, a tank having a discharge opening, a valve controlling said opening, a valve-rod for operating the valve, a heating chamber about the valve, and a 125 heating coil about the valve-rod.

12. In a tank car, a tank having a discharge opening, a valve controlling said

opening, a valve-rod for operating the valve, a heating chamber about the valve, and a heating coil about the valve-rod, said heating coil and chamber being in communication with each other.

13. In a tank car, a tank, an inlet header in the tank, an outlet header in the tank, heating conduits having their respective ends connected to said headers, a discharge opening from the tank, a chamber surrounding the opening, a valve controlling the opening, a valve rod for operating the valve, a pipe

coil surrounding the valve rod and connected to the inlet header and the outlet header, and a connection between the outlet header and said chamber.

In testimony whereof I have hereunto signed my name in the presence of two subscribing witnesses.

WM. M. HUTCHISON.
